8 Claims. (Cl. 315—241)

This invention is related to a flash lamp system and more particularly to a circuit for controlling the flashing of the lamp.

Flash lamps have found many uses in present day computer systems and the present invention has particular application in a computer system which employs a cathode ray tube printer to record the output. As is well known, the output information from the computer is displayed on the screen of a cathode ray tube and then recorded on film through suitable photographic means. In such a system it is oftentimes desired to record at selected places on the film a form or page outline within which the information from the computer will be positioned. The form outline is generally recorded by means of a flash lamp which is fired under control of a signal from the computer and in the past if the signal should fail to fire the lamp for some reason, such as aging or overheating of the bulb, the computer would be immediately locked up.

A bulb may miss one flash in a 100,000 tries but this does not necessarily mean that the bulb should be replaced or that it will not be capable of another 100,000 flashes and it would be preferred not to lock the computer when the lamp fails to flash but rather to attempt to fire the lamp a second or third time if necessary.

Accordingly, the main object of the present invention is to provide a control circuit operative to fire a flash lamp, said circuit including means for automatically effecting a repeat operation whenever the lamp fails to fire.

A further object of the present invention is to provide a starter circuit for firing a flash lamp in response to a computer signal and means included in said circuit for sending a recognition signal back to the computer in response to the firing of the lamp.

Other objects of the invention will be pointed out in the following description and claims and illustrated in the accompanying drawing, which discloses, by way of example, the principle of the invention and the best mode, which has been contemplated, of applying that principle.

A diagrammatic illustration of the invention is shown in the accompanying drawing and viewed broadly, the present invention provides a relay operated pulse transformer circuit for initiating lamp starting and a resistance capacitance coupled cathode follower circuit for controlling repetitive lamp starting operations.

In the operation of the circuit, a positive input signal (−30 to +10 volts, for example) from a computer or other suitable source is applied to terminal 10 to raise the potential of control grid 11 and switch tube T1 to a conducting state. Connected to the output of tube T1 is a relay R1 which is energized to close the contacts R1a and R1b. In parallel with the contacts R1a is a capacitor 12 connected between ground and a source of 300 volts so that it is normally charged to 300 volts and closure of the R1a contacts will cause the capacitor 12 to discharge into the primary winding 13 of a pulse trans-

former 14. As a result, a very high potential is induced across the secondary winding 15 of the transformer which initiates the starting of a flash lamp L. A capacitor 16 is in parallel with the lamp L and connected between ground and a source of 800 volts will now discharge into the lamp causing a high intensity flash. With current flowing in the lamp a resistor 17 in series with the lamp generates a recognition signal which may be sent back to the computer via terminal 18 indicating that the lamp

5 has flashed and instructing the computer to pull the input signal supplied to the terminal 10 down to −30 volts. For example, a conventional trigger T in the computer may be provided, the output of which normally places the input terminal 10 of the lamp circuit at a negative 30 volt potential. A suitable pulse on the set line will switch the trigger to effect a rise in potential to positive 10 volts at the terminal 10 causing the flash lamp circuit to operate. A resulting recognition signal developed across resistor 17 may be sent via the terminal 18 to a suitable amplifier A, the output of which is connected to the reset line of the trigger T. Accordingly, the trigger will be switched back to its normal state, indicating that the lamp has flashed, and the potential at terminal 10 will drop back down to negative 30 volts to render the lamp circuit inoperative. If the lamp had failed to flash, a signal would not have been developed across resistor 17 and the trigger will remain set keeping the potential at terminal 10 up to cause a repeat operation of the lamp circuit.

15 Along with the closing of contacts R1a contacts R1b also close and a capacitor 19 in parallel with the contacts R1b and connected between ground and the 300 volt source is discharged thereby lowering the potential at the point 20. Connected between the point 20 and the 20 control grid 21 of a cathode follower 22 are normally conducting neon tubes 23 which are extinguished upon the discharge of capacitor 19 resulting in a lowering of the potential on the control grid 21. The output of the 25 cathode follower is connected to the screen grid 24 of the tube T1 and the lowering of potential on the grid 21 reduces the cathode follower output sufficiently to drive the screen grid 24 below cutoff and turn tube T1 off. As a result, the relay R1 drops out opening the contacts R1a and R1b.

30 Capacitor 19 is such that it takes approximately 100 milliseconds after the contacts R1b open for the capacitor to charge back up to 300 volts after which time the output of cathode follower 22 is raised thus raising the potential at the screen grid 24 and conditioning tube T1 for operation again. During this time the capacitors 12 and 16 also recharge to prepare the circuit for service again. The delay of 100 milliseconds is provided to keep the number of flashes per second to 10 so as not to exceed the rating of power on the flash 35 lamp.

40 If the lamp should fail to flash, as is the case at times due to bulb aging or bulb heating, there will not be a recognition signal available at the terminal 18 for transmission back to the computer and as a result the signal at terminal 10 will not be pulled down but will remain at +10 volts. After the 100 millisecond delay, relay R1 is again energized and the circuit will repeat operation. As was previously mentioned, the repetitive feature of the circuit is very desirable because it lengthens the useful life of the lamp and the absence of the flash does not lock up the computer as is the case with a one and only one shot system.

45 In the preferred embodiment of the invention the pulse transformer is fed from a relay circuit rather than the customary thyratron discharge. The relay allows the pulse transformer to ring at its natural frequency thus

giving several pulses and insuring greater reliability in firing of the lamp.

While there have been shown and described and pointed out the fundamental novel features of the invention as applied to a preferred embodiment, it will be understood that various omissions and substitutions and changes in the form and details of the device illustrated and its operation may be made by those skilled in the art, without departing from the spirit of the invention. It is the intention, therefore, to be limited only as indicated by the scope of the following claims.

What is claimed is:

1. In an illuminating apparatus employing a flash lamp, a starter circuit responsive to an input signal means to supply above normal voltage to said lamp to cause same to flash momentarily, means associated with said lamp for generating an output signal upon flashing of the lamp, means responsive to said output signal for controlling said input signal means to render said starter circuit inoperative, and a control circuit responsive to said input signal means and including means for effecting repetitive operation of said starter circuit only in the event said lamp fails to flash, said repetitive operation continuing until said lamp flashes.

2. In an illuminating apparatus employing a flash lamp, an electron discharge device responsive to an input signal, a starter circuit responsive to the output of said discharge device to supply above normal voltage to said lamp to cause same to flash momentarily, means associated with said lamp for generating an output signal for controlling the termination of said input signal upon flashing of the lamp, and a control circuit responsive to the output of said discharge device and including means for conditioning said discharge device to effect repetitive operation of said starter circuit upon the absence of said output signal.

3. In an illuminating apparatus employing a flash lamp, an electron discharge device responsive to an input signal, a starter circuit responsive to the output of said discharge device to supply above normal voltage to said lamp to cause same to flash momentarily, means associated with said lamp for generating an output signal for controlling the termination of said input signal upon flashing of the lamp, and a control circuit responsive to the output of said discharge device and including means for switching said discharge device from an operative state to an inoperative state, and time delay means for conditioning said discharge device for repeat operation to effect repetitive operation of said starter circuit upon the absence of said output signal.

4. In an illuminating apparatus employing a flash lamp, an electron discharge device responsive to an input signal, a starter circuit responsive to the output of said discharge device to supply above normal voltage to said lamp to cause same to flash momentarily, means associated with said lamp for generating an output signal for controlling the termination of said input signal upon flashing of the lamp, a cathode follower for controlling the operation of said discharge device, a capacitor for controlling the operation of said cathode follower, means for charging said capacitor, and switching means controlled by the output of said discharge device for discharging said capacitor to effect the switching of said discharge device from an operative state to an inoperative state, said switching means being effective when said discharge device is in an inoperative state to allow said capacitor to become charged whereby said cathode follower will condition said discharge device for repeat

operation to effect repetitive operation of said starter circuit upon the absence of said output signal.

5. In an illuminating apparatus employing a flash lamp, an electron discharge device responsive to an input signal, switching means responsive to the output of said discharge device, a starter circuit called into operation by said switching means upon operation of said discharge device to supply above normal voltage to said lamp to cause same to flash momentarily, a control circuit called into operation by said switching means upon operation of said discharge device to return said discharge device to an inoperative state, said control circuit including time delay means operating under control of said switching means when said discharge device is in an inoperative state to condition said discharge device for repeat operation.

6. In an illuminating apparatus employing a flash lamp, an electron discharge device responsive to an input signal, a relay in the output circuit of said discharge device, a starter circuit comprising a capacitor and pulse transformer for supplying above normal voltage to said lamp to cause same to flash momentarily, contacts of said relay in said starter circuit for calling same into operation in response to operation of said discharge device, a control circuit for switching said discharge device from an operative state to an inoperative state, and contacts of said relay in said control circuit for calling same into operation in response to operation of said discharge device.

7. In an illuminating apparatus employing a flash lamp, an electron discharge device responsive to an input signal, a relay in the output circuit of said discharge device, a starter circuit for supplying above normal voltage to said lamp to cause same to flash momentarily, contacts of said relay in said starter circuit for calling same into operation in response to operation of said discharge device, a control circuit comprising a cathode follower having its output connected to said discharge device to control the operation of same, a capacitor discharge circuit for controlling operation of said cathode follower, means for charging said capacitor, and other contacts of said relay included in said discharge circuit for discharging said capacitor to effect the switching of said discharge device from an operative state to an inoperative state, said other contacts being effective when said discharge device is in an inoperative state to allow said capacitor to become charged whereby said cathode follower will condition said discharge device for repeat operation.

8. In an illuminating apparatus employing a flash lamp, a starter circuit responsive to an input signal to supply above normal voltage to said lamp to cause same to flash momentarily, an electronic trigger device operable to provide said input signal, means associated with said lamp for generating an output signal upon flashing of the lamp, amplifier means connecting said output signal to said trigger device whereby said trigger switches to cause termination of said input signal, and a control circuit responsive to said input signal and including means for effecting repetitive operation of said starter circuit upon the absence of said output signal.
